[57] CLAIM

The ornamental design for a combined bottle and cap, as shown and described.

DESCRIPTION

FIG. 1 is a side elevational view of a combined bottle and cap showing my new design;

FIG. 2 is a side elevational view thereof, rotated 30° from FIG. 1;

FIG. 3 is a side elevational view thereof, rotated 45° from FIG. 1;

FIG. 4 is a top plan view thereof;

FIG. 5 is a bottom plan view thereof;

FIG. 6 is a side elevational view of a second embodiment of the combined bottle and cap;

FIG. 7 is a side elevational view of the second embodiment rotated 30° from FIG. 6;

FIG. 8 is a side elevational view of the second embodiment rotated 45° from FIG. 6;

FIG. 9 is a top plan view of the second embodiment; and

FIG. 10 is a bottom plan view of the second embodiment.
